Co., Inc., Valencia, Pa., a corporation of Pennsylvania
Filed July 13, 1964, Ser. No. 382,004
8 Claims. (Cl. 101—40)

This invention relates to bottle decorating apparatus, and more particularly to improvements in bottle decorating apparatus of the intermittent motion type.

As is known, bottle decorating apparatus of the intermittent motion type have certain essential elements in common. These elements are: at least one decorating device which includes at least one stationary decorating squeegee and an associated stencil screen; an endless conveyor mounted on a base with a portion thereof adapted to move along a straight-line path of travel relative to the decorating device; sprockets at each end of the base engaged with the endless conveyor and about which the endless conveyor turns so as to reverse its direction of travel; a plurality of clamping devices secured at uniformly spaced points on the endless conveyor and adapted to support the workpieces in a horizontal position during their travel through the machine; at least one registration station wherein the workpiece surface to be decorated is oriented with respect to the decorating device; and drive means for imparting intermittent traveling motion to the endless conveyor.

In conventional decorating machines of this type, each of the clamping devices is moved from position to position and is brought to a complete rest at each of the positions. When each of the clamping devices are at a decorating position, i.e., directly opposite to the squeegee means of the decorating device, the clamping device must be elevated toward the stencil screen, rotated during the decoration of the bottle, and then lowered into its normal position prior to movement to the next position.

In certain of these conventional decorating apparatus, the halting, the elevating, the rotating and the lowering of each of the clamping devices is done sequentially. It should be evident then that a considerable amount of time is lost in performing these operations.

In certain other conventional decorating machines of this type, which are improvements over the aforementioned decorating machine, each clamping device is simultaneously elevated while being brought to a complete stop at the decorating position, a driving member is engaged with the base chuck for rotating the bottle during decoration. At the completion of the decorating process, the driving member is disengaged from the base chuck and the clamping device is simultaneously lowered into its normal position relative to the base while being moved to the next position. As can be seen, some operating time still is lost in that the driving member still must be engaged with and disengaged from the base chuck.

The lost operating time could be employed more profitably in decorating bottles. That is to say, if the lost time could be substantially entirely eliminated, the number of bottles which could be decorated in given length of time would be greater than in any of the conventional decorating apparatus.

2

Another disadvantage of these conventional decorating machines of the type described, is that they are relatively expensive to purchase. The purchase cost is directly related to their size. These conventional decorating machines have a predetermined number of the clamping assemblies mounted on the endless conveyor. A certain number of these clamping assemblies always is moving along a horizontal, straight-line path of travel. The length of the path of travel is determined by the spacing between the clamping assemblies. During the movement of each clamping assembly along the path of travel, it is positioned at a loading station, a registration station, one or more decorating stations, and an unloading station. Because of spacing problems, it has heretofore been required that each station be separated by a certain number of the clamping assemblies. For example, the distance between the loading station and the registration station is equal to the spacing between at least three of the clamping devices. Likewise, the distance between the registration station and the first decorating station also is equal to the spacing of at least three of the clamping devices. Further, the distance between the last decorating station and the unloading station is equal to the spacing between five to seven of the clamping devices depending on the length of the stencil screen. The distance between the decorating stations is always dictated by the length of the stencil screen and therefore may not be changed.

In one embodiment of a conventional decorating machine of the type described, the clamping devices were spaced at four-inch centers, the decorating stations were twenty-four inches apart, the distance between the registration station and the first decorating station was 20 inches, the distance between the loading station and the registration station was 16 inches, while the distance between the last decorating station and the unloading station was 36 inches. There were fifty-seven of the clamping devices secured to the endless conveyor. This decorating machine was greater than fifteen feet in length.

Accordingly, the primary object of the present invention is to provide decorating apparatus of improved design.

Another object of the present invention is to provide decorating apparatus of improved design wherein the number of clamping assemblies heretofore required has been reduced to a minimum whereby the cost of the decorating apparatus as well as its overall length have been significantly reduced.

Still another object of the present invention is to provide decorating apparatus having a significantly higher production rate than any of the conventional decorating apparatus heretofore available. In this respect, one or more colors and/or designs may be imprinted on the workpieces at a relatively high rate of speed.

A further object of the present invention is to provide decorating apparatus of the intermittent motion type having novel means for rotating the workpieces during their registration and decoration.

Yet another object of the present invention is to provide decorating apparatus of the intermittent motion type having novel means for maintaining the workpieces in the registered orientation during transfer between the registration position and the first decorating position as

well as between the first and second decorating positions. In accordance with the present invention, there is provided an improved decorating apparatus for applying decorative imprints to generally cylindrical workpieces, such as bottles. The present decorating apparatus is of the intermittent motion type including a plurality of clamping assemblies mounted at uniformly spaced points on an endless conveyor supported for movement along a straight-line path of travel. Drive means is provided for imparting intermittent traveling motion to the endless conveyor whereby each of the clamping assemblies is brought to complete rest at a plurality of consecutive, spaced positions along the path of travel of the endless conveyor. The present decorating apparatus also is provided with at least one decorating device which includes a stationary squeegee and a movable stencil screen. In the drawings accompanying this specification, the present decorating apparatus is illustrated as having two decorating devices. It should be understood, however, that the principles disclosed in the present invention are applicable equally to decorating apparatus having one or a plurality of decorating devices.

The present decorating apparatus also is provided with transfer apparatus which includes traveling clamping devices for transferring workpieces individually, for example, from a feed location which is spaced from the endless conveyor to a loading position on said conveyor. Furthermore, a second transfer device is provided which also includes traveling clamping devices for transferring the decorated workpieces from an unloading position on the endless conveyor to a discharge conveyor which is spaced from the decorating apparatus.

The present decorating apparatus is further provided with a novel cam track arrangement which extends around the endless conveyor and is parallel therewith. Each of the clamping assemblies is operatively connected to the cam track. The cam track includes a plurality of segments each of which is mounted for rotation about an axis parallel with and preferably coincident with the axis of rotation of the workpiece carried by the clamping assembly. One cam track segment is provided at the registration position and at each of the decoration positions. The arrangement is such, that each clamping assembly is brought to a complete rest, for example, at the registering position whereupon the cam track segment disposed therein is rotated to rotate the workpiece carried by the clamping assembly. After each workpiece has been registered, its registered orientation with respect to the stencil screen is maintained by the cam track, as will be described.

In the present decorating apparatus, the workpieces are individually loaded on a clamping assembly which is disposed in a first idle position, that clamping assembly is moved to a second idle position which comprises a registering position, and thereafter that clamping assembly is moved to a third idle position which comprises a first decorating position. Hence, the loading, registering and first decorating of a workpiece is accomplished within three consecutive positions of the supporting clamping assembly. That clamping assembly then is moved to a second decorating position for the application of a second color or imprint on the workpiece. Thereafter that clamping assembly is moved to an unloading position where the decorated workpieces are picked up by the second transfer device for discharge from the decorating apparatus.

As will become apparent later in the specification, each clamping assembly when in the first and second decorating positions is disposed perpendicular to the path of travel of the endless conveyor. However, each clamping assembly when at the loading position, the registering position and the unloading position, is inclined with respect to the horizontal path of travel of the endless conveyor. Furthermore, those workpieces which are disposed at the loading position, the registering position or the un-

loading position, are disposed below those workpieces moving along the horizontal straight-line path of travel of the endless conveyor between the first and second decorating positions.

The above and other objects and advantages of the present invention will become apparent from the following detailed description by reference to the accompanying drawings, in which:

FIG. 1 is a side view of a decorating apparatus constructed according to the principles of the present invention;

FIG. 2 is a fragmentary cross-sectional view schematically illustrating a drive means for imparting intermittent traveling motion to an endless conveyor employed in the present decorating apparatus;

FIG. 3 is a schematic illustration of a drive train employed in the present decorating apparatus;

FIG. 4 is a fragmentary cross-sectional view illustrating a cam track assembly employed in rotating each workpiece and for maintaining its registered orientation with respect to the stencil screen;

FIG. 5 is a cross-sectional view, taken along the line V—V of FIG. 1, illustrating a clamping assembly employed in the present decorating apparatus;

FIG. 6 is a fragmentary plan view, with portions cut away to show details, illustrating a rotatable cam track segment employed in rotating the workpieces during registration and decoration; and

FIG. 7 is a cross-sectional view, taken along the line VII—VII of FIG. 5, illustrating a registering mechanism employed in the present decorating apparatus.

DECORATING APPARATUS—GENERAL DESCRIPTION

Reference is now directed to FIGS. 1 and 2 wherein the present decorating apparatus is generally indicated by the numeral 10. The decorating apparatus 10 comprises a base 12 having a pair of opposed side plates 14 (only one visible) upon one end of which is rotatably mounted a pair of idler sprockets 15 and upon the other end of which is rotatably mounted a pair of drive sprockets 16. The pairs of sprockets 15, 16 are connected by shafts 17a and 17b, respectively. Extending between and around the sprockets 15, 16 is an endless conveyor 18. A plurality of clamping assemblies 20 are secured at uniformly spaced points along the endless conveyor 18. The endless conveyor 18 includes an upper reach 22 adapted to move along a horizontal, straight-line path of travel between the sprockets 15, 16. Each of the clamping assemblies 20 is adapted to support a workpiece 24 for conveyance along the straight-line path of travel.

As can be seen in FIG. 2, the decorating apparatus 10 is provided with a drive means 26 which imparts intermittent traveling motion to the conveyor 18, i.e., the conveyor 18 is advanced step-by-step, each step movement advancing the conveyor the distance between the centers of two adjacent clamping assemblies 20. The drive means 26 is supported on the base 12 at one side of the decorating apparatus 10.

The drive means 26 is conventional and comprises a cam and gear assembly 32 having an input shaft 34 and an output shaft 36. The input shaft 34 is driven at a constant r.p.m. while the output shaft 36 is driven intermittently by means of the cam and gear assembly 32. The output shaft 36 is connected in driving relation with the shaft 17b thereby imparting intermittent motion to the pair of sprockets 16 and the endless conveyor 18.

Referring again to FIG. 1, the decorating apparatus 10 is provided with first and second decorating devices generally indicated by the numerals 48 and 50. Each of the decorating devices 48, 50 includes a stationary squeegee means 52 which is positioned along a horizontal arm 54 suitably mounted on the base 12. The stationary squeegee means 52 may comprise any suitable squeegee and preferably comprises that squeegee means described and shown in copending application Ser. No. 262,714, filed Mar.

4, 1963 and assigned to the assignee of the present application. Each of the first and second decorating devices, additionally includes a stencil screen 56 mounted for reciprocable horizontal movement. The mechanism employed for reciprocating the stencil screens 56 is conventional in the art and may comprise, for example, that mechanism shown and described in U.S. Patent No. 2,231,535. For the purposes of the present invention, however, it will be sufficient to state that the stencil screen 56, for example, associated with the first decorating device 48 will be moved to the left of FIG. 1 into the position indicated in dotted outline at 56' during the decoration of one of the workpieces 24. During the decoration of the next workpiece, the stencil screen is moved to the right of FIG. 1 from the position indicated at 56' to the position indicated in full lines at 56. Furthermore, it should be understood that during the decorating operation of the apparatus 10, both of the stencil screens 56 are moved in unison to the left, and then to the right of FIG. 1.

The present decorating apparatus 10 also is provided with first and second transfer mechanisms generally indicated by the numerals 58 and 60. The first transfer mechanism 58 is employed in transferring the bottles 24 from a feed conveyor, schematically illustrated at 62, to a clamping assembly 20 which is disposed in a predetermined position with respect to the first decorating device 48, as will be described. The second transfer mechanism 60 is employed in transferring decorated bottles 64 from one of the clamping assemblies disposed in a predetermined position with respect to the second decorating device 50, as will be described, to a discharge conveyor schematically illustrated at 66. The first and second transfer mechanisms 58, 60 include a drive shaft 68, 70, respectively, which supplies the power for their operation.

The present decorating apparatus is additionally provided with a cam track assembly 72 with which each of the clamping assemblies 20 is operatively connected. The cam track assembly 72 extends parallel with the path of travel of the endless conveyor 18. As will be more fully described later in the specification, the cam track assembly 72 includes a plurality of rotatable cam track segments which serve to rotate the workpieces 24 during their registration and their decoration.

Reference is now directed to FIG. 3 wherein there is schematically illustrated a driving train 74 employed in the present decorating apparatus 10. It should be understood at this time that the driving train 74, as illustrated in FIG. 3, shows only the various drive components required by the present decorating apparatus 10 and that their positions, relative to one another are actually not as shown. The driving train 74 includes a main drive motor 76 which is operatively connected to a variable speed reducer 78. The variable speed reducer 78 is, in turn, operatively connected to and drives a main drive shaft 80. At each end of the main drive shaft 80, there is provided a set of miter gears 82, 84 which connect the main drive shaft to fixed ratio speed reducers 86, 88. The speed reducer 86 is connected to the first transfer mechanism 58 (FIG. 1) by means of the drive shaft 68, while the speed reducer 88 is connected to the second transfer mechanism 60 (FIG. 1) by means of the drive shaft 70. Also connected to the main drive shaft 80, by means of a chain drive 90 is the drive means 26 which, as described above, serves to impart intermittent traveling motion to the endless conveyor 18. Operatively connected to the drive shaft 80 are first and second screen drives 92, 94. The first screen drive 92 serves to reciprocate the screen 56 associated with the first decorating device 48 (FIG. 1) while the second screen drive 94 serves to reciprocate the stencil screen 56 of the second decorating device 50 (FIG. 1). Alternatively, a single screen drive may be used to reciprocate both of the stencil screens 56 of the first and second decorating devices 48, 50.

Inspection of FIG. 3 will reveal that the speed reducers 86, 88, the first and second screen drives 92, 94, and the conveyor drive means 26 operate in synchronism. The variable speed reducer 78 provides a means by which the speeds of operation of the drive means 26, the variable speed drives 86, 88, and the first and second screen drives 92, 94 may be varied in unison to increase or decrease the production rate of the decorating apparatus 10.

CLAMPING ASSEMBLIES 20

Reference is now directed to FIG. 5 wherein there is illustrated one of the clamping assemblies 20. As can be seen, each of the clamping assemblies 20 includes a crossplate 96 having a base chuck 98 and a neck chuck 100 secured at opposite ends thereof. The base chuck 98 includes a shaft 102 which is supported for rotation about a horizontal axis which is coincident with the rotational axis, indicated by the dashed-dot line 104, of the workpiece 24. Secured to the inboard end of the shaft 20 102 is a base cup 106 adapted to engage the bottom of the workpiece 24.

The neck chuck 100 is provided with a shaft 108 which is supported for reciprocal movement axially of the rotational axis 104. At the inboard end of the shaft 108 25 there is secured a neck cup 110 adapted to engage the neck of the workpiece 24. The neck cup 110, shown in full lines, is in a clamping position while the neck cup also is illustrated in dotted outline at 110' in a retracted position. The neck chuck 100 preferably comprises that 30 neck chuck shown and described in copending application Ser. No. 356,198, filed Mar. 31, 1964, and assigned to the assignee of the present invention. For the purposes of the present invention, however, it will be sufficient to state that the neck chuck 100 is pneumatically 35 operated and includes conduits 112, 114 extending from the neck chuck 100 to a valve means 116. Associated with the shaft 108 is a piston (not shown) which is housed within the neck chuck 100. In operation, the conduit 112 serves to introduce fluid under pressure on 40 one side of the piston to displace the neck cup 110 into engagement with the workpiece 24. Conversely, fluid introduced on the opposite side of the piston by the conduits 114 displaces the neck cup 110 away from the workpiece 24 into the position illustrated at 110'.

45 The valve means 116 includes a valve operator 118 which controls the introduction of fluid into either of the conduits 112, 114. The valve operator 118 includes an actuating arm 120 which, when displaced in the direction indicated by the arrow 122, will cause the fluid under 50 pressure to be introduced into the conduit 112. Conversely, when the actuating arm 120 is displaced in a direction indicated by the arrow 124, air is introduced through the conduit 114. The actuating arm 120 preferably is spring-biased in a vertical position illustrated in 55 FIG. 5. Hence, cam means (not shown) may be provided at the loading and unloading positions of the decorating apparatus 10 one of which actuates the valve means 116 for clamping of a workpiece 24 between the neck cup 110 and the base cup 106 and the other of 60 which actuates the valve means 116 for releasing the workpiece 24 from the clamping device 20.

Each crossplate 96 of each of the clamping devices 20 is connected to the endless conveyor 18 by means of 65 later in the specification, the workpiece 24 carried by each of the clamping assemblies 20, when in the first or second decorating position, is disposed very near the stencil screen 56. After the workpiece 24 has been decorated, the clamping assembly 20 is moved to the 70 next position whereupon the entire clamping assembly is lowered. The lowering of each clamping assembly is limited by the engagement of the chain segments 126 with the inwardly extending flanges 128 of the side plates 14. The lowering of each of the clamping assemblies 75 20 after the workpiece 24 has been decorated at the first

decorating position, is necessary so that as the stencil screen 56 is reciprocated it will not engage the previously decorated workpiece thereby causing blurred or smeared imprints.

TRANSFER MECHANISMS 58, 60

Referring again to FIG. 1, the first and second transfer mechanisms 58, 60 preferably comprise that transfer mechanism described and illustrated in copending application Ser. No. 382,005, filed July 13, 1964, and assigned to the assignee of the present invention. The operation of the first and second transfer mechanisms 58, 60 is identical with that operation disclosed in the aforesaid copending application Ser. No. 382,005. For the purpose of the present invention, however, it will be sufficient to state that each of the first and second transfer mechanisms 58, 60 includes four traveling clamping devices 146a-146d. The traveling clamping devices 146a of both transfer mechanisms 58, 60, are hidden from view since they are directly behind clamping device 146c. The traveling clamping devices 146a, as illustrated in FIG. 1, are positioned adjacent to the feed conveyor 62 and the discharge conveyor 66. The traveling clamping assemblies 146a-146d are equiangularly spaced about the carrier 148 and are supported thereon for reciprocal movement parallel to the longitudinal axis of the carrier 148. Further, the carrier 148 is supported for rotation about its longitudinal axis, illustrated by the dash-dot line at 149. A drive mechanism 150 serves to rotate the carrier 148 as well as reciprocate the traveling clamping devices 146a-146d.

In operation, the carrier 148 is rotated intermittently through 90° of movement by means of a conventional Geneva drive. Simultaneously with the intermittent rotation of the carrier 148, the traveling clamping devices 146a-146d are moved continuously back and forth along a path parallel to the longitudinal axis of the carrier 148. The relative positions of the traveling clamping devices 146a-146d with respect to one another is illustrated in FIG. 1. For example, in the first transfer mechanism 58 the traveling clamping device 146a (not visible) is disposed on one side of the carrier 148 and at a midpoint thereon. The traveling clamping device 146b is disposed at the top of the carrier 148 and at the forward end thereof adjacent to the endless conveyor 18. The traveling clamping device 146c is disposed on the side of the carrier 148 opposite to the traveling clamping device 146a, and at a midpoint on the carrier 148. The traveling clamping device 146d is disposed beneath the carrier 148 and at the end of the carrier 148 opposite the traveling clamping device 146b. The position of the traveling clamping devices 146b-146d relative to one another of the second transfer mechanism 60 is identical to that of the first transfer mechanism 58. Consequently, when the traveling clamping device 146a is moved from that position illustrated on the first transfer mechanism 58 to the position now occupied by the traveling clamping device 146b, the traveling clamping device 146 undergoes (1) linear movement toward the decorating apparatus 10; (2) simultaneous linear movement toward the decorating apparatus 10 and rotational movement about the longitudinal axis of the carrier 148; and (3) linear movement toward the decorating apparatus 10 to arrive at the position now occupied by the traveling clamping device 146b.

Each of the traveling clamping devices 146a-146d clamps one of the workpieces 24 fed thereto by means of the feed conveyor 62 when they are in the position of the clamping device 146a of the first transfer mechanism 58. Notice that the workpiece 24 is oriented in a vertical position. Thereafter, the traveling clamping devices will move to that position now occupied by the traveling clamping device 146b. In this position, the clamping device releases the workpiece 24 which now is oriented horizontally, so that it may be transferred to and clamped

by one of the clamping assemblies 20. For a complete description of the construction and operation of the first and second transfer mechanisms 58, 60, reference is directed to the aforementioned copending application Ser. No. 382,005.

OPERATIONAL POSITIONS OF THE CLAMPING ASSEMBLIES 20

Indicated in FIG. 1, are five positions wherein the clamping assemblies 20 are operative. These positions are indicated by dash-dot lines which are labeled and numbered as follows: a loading position 152, a registering position 154, a first decorating position 156, a second decorating position 158 and an unloading position 160. As should be evident, the workpieces 24 are loaded onto one of the clamping assemblies 20 at the loading position 152 and thereafter are moved, in order, to the registering position 154 wherein they are registered with respect to the stencil screens 56; the first and second decorating positions 156, 158 wherein, for example, two colors of a decorative imprint are applied to the workpieces; and then moved to the unloading position 160 wherein the decorated bottles 64 are transferred from the clamping assemblies 20 to the discharge conveyor 66.

It is important to note that in the decorating apparatus 10, the clamping assemblies 20 are perpendicular to the horizontal path of travel of the upper reach 22 of the endless conveyor 18 when the clamping assemblies 20 are disposed at the first and second decorating positions 156, 158 or at positions therebetween. Furthermore, when each of the clamping assemblies 20 are positioned at the loading position 152, the registering position 154, and the unloading position 160, are inclined or angularly disposed with respect to the horizontal path of travel of the upper reach 22 of the endless conveyor 18. Thus, loading, registering, and unloading of the workpieces occurs at the positions which are beneath the positions of those workpieces disposed at the first and second decorating positions 156, 158 or at points therebetween. It is also important to note, that the loading, the registering and first decorating of each of the workpieces 24 occurs at consecutive positions in the step-by-step movement of the clamping assemblies 20. As described above, it was heretofore necessary to provide a plurality of the clamping assemblies between the loading position and the registering position as well as a second plurality of the clamping assemblies between the registering position and the first decorating position. It was likewise necessary, heretofore, to provide a plurality of the clamping assemblies between the second decorating position and the unloading position. However, in the present decorating apparatus only one clamping assembly is necessary between the second decorating position 158 and the unloading position 160. Accordingly, the length of the endless conveyor 18 of the present decorating apparatus 10 has been reduced considerably. Furthermore, the number of clamping assemblies required has also been considerably reduced. For example, the decorating apparatus 10 illustrated in FIG. 1 employs twenty of the clamping assemblies 20 whereas in a similar decorating apparatus constructed in accordance with the prior art must of necessity employ fifty-seven of the clamping devices. The above stated numbers are based on the clamping devices being spaced at four-inch centers and the first and second decorating positions 156, 158 being spaced by twenty-four inches center-to-center.

Another advantage of the present decorating apparatus 10 over the prior art decorating apparatus, is that in the present decorating apparatus 10, the first and second transfer mechanisms 58, 60 may be operated to load and discharge two-hundred workpieces or bottles per minute. Hence, the speed of operation of the present decorating apparatus is limited only by the speed with which the first and second decorating devices 48, 50 may decorate the workpieces. With the advent of thermoresponsive

coloring mediums, the speed of decorating the workpieces has been tremendously increased. In these thermo-responsive coloring mediums, the pigmented materials are carried in thermoresponsive vehicles which, when heated above room temperature, are of thin, paste-like consistency, ideally suited for screen stencil work, but which freeze or solidify immediately upon being applied to the relatively cooler surfaces of the workpieces which are at room temperature.

Broadly then, the present invention provides a decorating apparatus which is relatively inexpensive to manufacture in that the overall length of the conveyor has been considerably reduced from that length heretofore required. Furthermore, the operating speed of the present decorating apparatus 10 is significantly greater than the operating speeds of the decorating apparatus heretofore available.

REGISTRATION

Registration of each of the workpieces 24 is accomplished at the registering position 154. The mechanism for registering the workpieces 24 is illustrated in FIG. 7. This mechanism is conventional and may comprise, for example, a registration finger 161 which is moved into engagement with the outer surface of the workpieces 24 by means of a pneumatic piston 162. As is conventional in the art, a lug 163 is formed or cast in the workpiece at a suitable location. The lug 163 facilitates precise locating of the workpiece 24 with respect to the stencil screen 56 for registration of single or successive decorative imprints. Hence, when the workpiece 24 is rotated, as will be described, the lug 163 is moved into engagement with the registration finger 161 whereupon the workpiece 24 is prevented from further rotation. As can be seen in FIG. 1, the pneumatic piston 162 is positioned so that the registration finger 161 is displaced toward the workpieces 24 in the direction of travel of the endless conveyor 18. This position is preferred, since, the registration finger 161 can be retracted simultaneously with moving the endless conveyor 18 through its next stepwise movement. Hence, no lost time is incurred in first retracting the registration finger 161 and then moving the endless conveyor, as is the case in conventional decorating apparatus.

CAM TRACK ASSEMBLY 72

Reference is now directed to FIG. 4 wherein the cam track assembly 72 is schematically illustrated. The cam track assembly 72 comprises a plurality of stationary cam track segments 164 and a plurality of rotatable cam track segments 166a-166c. The cam track segments 164, 166a-166c cooperate to define a guideway extending parallel to the path of travel of the clamping assemblies 20 (FIG. 5). Hence, the rotatable cam track segments 166a-166c form continuations of the stationary cam track segments 164 and are normally positioned in alignment therewith, as illustrated in FIG. 4, during the intermittent movement of the endless conveyor 18. The stationary cam track segments 164 and the rotatable cam track segments 166a-166c preferably are channel-shaped whereby they are adapted to receive cam followers as will be described.

As can be seen in FIG. 4, the rotatable cam track segment 166a is positioned at the registering position 154 and is rotatable about an axis which is parallel with and preferably coincident with the rotational axis 104 (FIG. 5) of the workpiece 24. The rotatable cam track segment 166a is rotated in a counterclockwise direction, as indicated by the arrow, by means of a suitable drive motor schematically illustrated at 168. Similarly, the rotatable cam track segments 166b and 166c are positioned, respectively, at the first and second decorating positions 156, 158. The rotatable cam track segments 166b and 166c, each is rotatable about an axis which is parallel with and preferably coincident with the rotational axis 104 (FIG. 5) of the workpieces 24. The rotatable cam track segments 166b and 166c are rotated

simultaneously in a clockwise direction and then in a counterclockwise direction by means of a drive motor schematically illustrated at 170 and a suitable shafting arrangement schematically illustrated at 172.

Referring now to FIGS. 5 and 6, the base chuck 98 of each of the clamping assemblies 20 has associated therewith a cam follower or roller 176 which is rotatably connected to one end of a lever arm 178. The lever arm 178 is connected at its other end to the outboard end of the shaft 102 of the base chuck 98. Hence, as can be seen in FIG. 5, rotation of the lever arm 178 will cause rotation of the workpiece 24.

In FIGS. 5 and 6, the clamping assembly 20 is shown positioned in alignment with one of the rotatable cam track segments 166 which may comprise either of the rotatable cam track segments 166a-166c of FIG. 4. As explained above, the rotatable cam track segment 166 is rotated by means of the drive motor 168 or 170. As can best be seen in FIG. 6, rotation of the rotatable cam track segment 166 will cause rotation of the arm 178 as well as the workpiece 24. It will be evident by inspection of FIG. 5, that although it is preferred that the rotational axis of the cam track segment 166 be coincident with the rotational axis 104 of the workpiece 24, this need not be the case, since, during rotation of the cam track segment 166 the cam follower 176 is free to roll within the C-shaped recess of the cam track segment 166. Hence, misalignments of about one-eighth of an inch can be tolerated without seriously affecting the transfer of the decorative imprints to the workpiece 24.

OPERATION

For the purpose of a fuller understanding of the operation of the present decorating apparatus 10, a single workpiece will be described during its travel from the feed conveyor 62 through the decorating apparatus 10 and to the discharge conveyor 66.

Referring now to FIG. 1, the first and second transfer mechanisms 58, 60 are operated continuously during the operation of the present decorating apparatus 10. That is to say, each of the traveling clamping devices 146a-146d will undergo movement from a point midway on the carrier 148 and adjacent to the feed conveyor 62 to that position now occupied by the clamping device 146b; thereafter to that position now occupied by the clamping device 146c; thereafter to that position now occupied by the clamping device 146d; and finally to return to a position directly opposite to the clamping device 146c.

The first transfer mechanism 158 will pick up one of the workpieces 24 from the feed conveyor 62 and transfer it to the loading position 152. Simultaneously, the workpiece 24 will be reoriented from a vertical position when on the feed conveyor 62 to a horizontal position when at the loading position 152. The workpiece 24, when disposed at the loading position 152, will be clamped between the bottom chuck 98 and the neck chuck 100 of the clamping assembly 20. The transfer of the workpiece 24 between the clamping device 146b, for example, to the clamping assembly 20 will occur during a pause in the intermittent motion of the endless conveyor 18.

During the next stepwise movement of the clamping assembly 20, the workpieces will be moved to the registering position 154. At the registering position 154, the pneumatic piston 162 will be activated to displace the registration finger 161 into engagement with the outer surface of the workpiece 24. Thereafter, the drive motor 168 will be activated to rotate the rotatable cam track segment 166a whereupon the workpiece 24 is rotated in a counterclockwise direction through exactly 360°. During rotation of the workpiece 24, the lug 163 (FIG. 7) will engage the registration finger 161 to prevent further rotation of the workpiece 24. In this position, the workpiece 24 is registered or properly oriented with respect to the stencil screen 56.

During the next stepwise movement of the endless conveyor 18, the registered workpiece 24 will be moved

from the registering position 154 to the first decorating position 156. Notice, however, that the roller 176 rolls within and is guided by the C-shaped recess of the cam track segments 164, 166. Hence, the registry of each workpiece 24 is maintained. As can be seen in FIG. 1, the surface of a workpiece to be decorated is moved into close proximity with the stencil screen 56. Hence, in the present decorating device 10, the pair of sprockets 15 comprise means for displacing each of the clamping assemblies 20 toward the first decorating device 48. During the pause in the intermittent travel of the endless conveyor 18, the pneumatic squeegee 52 is activated to lower the squeegee 180 into contact with the stencil screen 56. Thereafter, the stencil screen 56 is moved to the left of FIG. 1 into the dotted outline position indicated at 56'. The drive motor 170 (FIG. 4) is activated—operating in synchronism with the screen drives—to rotate the rotatable cam track segment 166b and the workpiece in a counterclockwise direction through exactly 360°. Hence, in effect, the workpiece rolls over the screen 56 during its passage across the workpiece.

After completion of the decorating operation at the first decorating position 156 the partially decorated workpiece 24 is moved step-by-step to the second decorating position 158. It should be noted that when the workpiece is moved from the first decorating position 156 to the next adjacent position, the clamping assembly 20 is lowered so that the chain segments 126 engage the inwardly extending flange 128 (FIG. 5) of the side plates 14. The lowering of the clamping assemblies 20 is necessary in order to prevent inadvertent smearing of the imprint applied by the first decorating device 48 during the subsequent lateral travel of the stencil screens 56.

When the partially decorated workpiece reaches the second decorating position 158, the clamping assembly 20 upon which it is supported is elevated whereby the surface of the partially decorated workpiece is again positioned close to the stencil screen 56 of the second decorating device 50. Hence, the pair of drive sprockets 16 comprises means for displacing each of the clamping devices toward the second decorating device 50. During the pause in the intermittent traveling motion of the endless conveyor 18, the pneumatic squeegee 52 is activated to lower the squeegee 180 into contact with the stencil screen 56. Thereafter, the stencil screen 56 is moved laterally across the workpiece for transfer, for example, of a second color of the decorative imprint applied to the workpiece. The drive motor 70 (FIG. 4) is again activated—operating in synchronism with the screen drives—to rotate the rotatable cam track segment 166c and the workpiece through exactly 360° in a clockwise or a counterclockwise direction, depending on the direction in which the stencil screen 56 is moved.

At the completion of the decorating operation at the second decorating position 158, the completely decorated workpiece is moved in a stepwise fashion to the unloading position 160 wherein one of the traveling clamping devices 146a-146d is positioned to clamp the completely decorated workpiece. Simultaneous with the clamping of the workpiece by one of the traveling clamping devices 146a-146d, the valve means 116 is activated to retract the neck chuck 110 thereby releasing the workpiece 24 from the clamping assembly 20. The transfer of the completely decorated workpiece from the clamping assembly 20 to one of the traveling clamping devices 146a-146d is accomplished during a pause in the intermittent traveling motion of the endless conveyor 18. The completely decorated workpiece then is transferred from the unloading position 160 to the discharge conveyor 66. It should be noted that the completely decorated workpiece is reoriented from its horizontal position when on the clamping assembly 20 to a vertical position when deposited on the discharge conveyor 66.

Although the invention has been illustrated in connection with one specific embodiment, it will be readily ap-

parent to those skilled in the art that various changes in form and arrangement of parts to suit requirements may be made without departing from the spirit and scope of the invention.

5 We claim as our invention:

1. In decorating apparatus wherein workpieces undergo intermittent traveling motion along a path of travel and are brought to complete rest at points along said path of travel, said workpieces being rotated about their central axes at at least one predetermined one of said points, the combination comprising: cam followers, one each connected with each of said workpieces for rotation therewith; guideway means comprising a plurality of aligned cam track segments extending parallel with said path of travel for receiving and guiding said cam followers; one of said cam track segments being positioned at said predetermined one of said points and supported for rotation about an axis parallel with the central axis of said workpiece; and means for rotating said one of said segments during pauses in the intermittent traveling motion of said workpieces.

10 2. The combination as set forth in claim 1 including means for supporting said cam followers in radially spaced relation relative to said central axes.

15 3. In decorating apparatus for applying decorative imprints to workpieces, said apparatus having endless conveyor means supported for movement along a path of travel, a registration station at which said workpieces are registered and at least one decorating station at which said decorative imprints are applied to said workpieces, a plurality of clamping assemblies secured to said endless conveyor each having a neck chuck and a base chuck adapted to support one of said workpieces for rotation about its central axis, and drive means for imparting intermittent traveling motion to said endless conveyor means whereby each of said clamping assemblies is brought to complete rest at a plurality of positions along said path of travel, one of said positions being aligned with said registration station and another of said positions being aligned with said decorating station, the improvement in means for rotating said workpieces when at each of said stations comprising: cam followers, one each connected with each of said workpieces; guideway means extending parallel to said path of travel for receiving and guiding said cam followers, said guideway means including first and second 20 rotatably supported segments, one each residing at said registration station and said decorating station; said first and second segments being positioned to receive each of said cam followers and being rotatable about axes parallel with the central axes of said workpieces; and means for rotating said first and second segments during pauses in the intermittent traveling motion of said endless conveyor.

25 4. The improvement of claim 3 wherein said registration station and said decorating station are disposed at consecutive ones of said positions at which said workpieces are brought to complete rest.

30 5. The improvement of claim 3 including means for displacing each of said clamping assemblies toward said decorating device simultaneously with bringing each of said clamping assemblies to complete rest opposite to said decorating device.

35 6. The improvement of claim 5 wherein said means comprises sprockets supporting said endless conveyor.

40 7. In workpiece decorating apparatus wherein workpieces are conveyed along a path of travel and are rotated about their central axes at at least one position along said path of travel, the combination comprising: cam followers, one connected to each of said workpieces for rotation therewith; guideway means engaged by said cam followers for guiding the same, said guideway means comprising a plurality of aligned cam track segments extending parallel with said path of travel, one of said cam track segments being positioned at said one position and being

13

supported for rotation about a rotational axis parallel with said central axes; said cam followers being guided successively into torque transmitting relation with said one of said cam track segments; and means for rotating said one of said cam track segments when engaged by each successive one of said workpieces.

8. The combination as set forth in claim 7 wherein said cam track segments are aligned to form a continuous track and wherein said cam followers are continuously engaged with said cam track segments.
